DESIGN FOR AN AUTOMOBILE

C. Charles Walker, Pittsburgh, Pa.

Application November 23, 1935, Serial No. 59,730

Term of patent 14 years

To all whom it may concern:

Be it known that I, C. Charles Walker, a citizen of the United States, residing at Pittsburgh, county of Allegheny, and State of Pennsylvania, have invented a certain new, original, and ornamental Design for an Automobile, of which the following is a specification, reference being had to the accompanying drawing, forming a part thereof.

Fig. 1 is a front perspective view of an automobile showing my new design;

Fig. 2 is a front elevational view;

Fig. 3 is a partial plan view to enlarged scale; and

Fig. 4 is a rear perspective view.

I claim:

The ornamental design for an automobile, as shown.

C. CHARLES WALKER.
